CLAIM

The ornamental design for an autonomous transport trolley, as shown and described.

DESCRIPTION

FIG. 1 is a front and left side perspective view of an autonomous transport trolley showing our new design; FIG. 2 is a rear and right side perspective view thereof; FIG. 3 is a front and right side perspective view thereof; FIG. 4 is a rear and left side perspective view thereof; FIG. 5 is a front elevational view thereof;

FIG. 6 is a rear elevational view thereof;

FIG. 7 is a top plan view thereof;

FIG. 8 is a bottom plan view thereof;

FIG. 9 is a right side elevational view thereof; and,

FIG. 10 is a left side elevational view thereof.

The broken lines shown in the drawings depict portions of the autonomous transport trolley that form no part of the claimed design. The grayscale shading of the drawings depict the shape of the three-dimensional surface and do not represent any particular colors.
